ABSTRACT OF THE DISCLOSURE

Adhesion of deposits to heat exchange metal surfaces in processing hydrocarbons at elevated temperatures (i.e. from about 150°–1000° F. or higher) is inhibited by an anti-fouling amount of an oxyalkylated N-substituted phenylene diamine, as exemplified by oxyalkylated N-phenyl-p-phenylene diamine, oxyalkylated N,N'-diphenyl-p-phenylene diamine and oxyalkylated N-cyclohexyl-N'-phenyl-p-phenylene diamine. Other additives can also be employed in conjunction with the above anti-foulants.

RELATED APPLICATION

ware

Status: Abandoned

SUMMARY OF THE INVENTION

This invention relates to a method of chemically treating hydrocarbon liquids which contact surfaces under high temperature conditions in order to inhibit, prevent and/or reduce the deposition of substances thereon. More specifically, this invention relates to the chemical treatment of the metal surfaces in contact with petroleum hydrocarbon liquids under conditions of high temperatures whereby said liquids tend to form deposits on such metal surfaces. This invention also relates to compositions employed in these processes.

In the processing of hydrocarbon liquids, particularly petroleum hydrocarbon liquids, elevated temperatures are often used in many necessary and important operations. To handle liquids at elevated temperatures, heat exchangers and the like devices are often employed to control the heat transfer rate from one operational step to another. When hydrocarbon liquids contact hot metal surfaces, there is sometimes a tendency for the liquid to decompose or undergo a chemical reaction that manifests itself in the form of deposits. These deposits may be either coke-like or they may be in the form of tenacious, soft, sticky sludges which adhere to hot surfaces. Adherences of deposits, rather than deposit-formation itself is the essence of the problem, in contrast to fuel storage where residue in the oil itself creates the problem.

The problem is well recognized in the art—note “Petroleum Products Handbook,” Guthrie (McGraw-Hill, 1960) pp. 1–13, U.S. Pat. 2,908,824 and elsewhere.

These deposits tend to materially decrease the heat transfer capacities of the metal surfaces and hence increase operating expenses. These deposits also require additional effort and time to remove and to restore the equipment to its original operating efficiency.

Petroleum refinery operations often encounter the above described conditions in many stages in the refining process. These deposits form on heat transfer surfaces at temperatures for example such as about 150–225° F. and

may be evidenced at temperatures as extreme as 1000° F. or higher.

It is practically impossible to prevent these deposits by coating the metal surfaces with a protective permanent coating due to the possible loss of heat transfer. In addition, the large volume of liquid that contacts such equipment increases the problem of treating metal surfaces in petroleum processing to prevent high temperature deposits.

10 It would be advantageous to add a chemical agent in extremely small amounts to a hydrocarbon liquid which tends to form high temperature deposits whereby such deposits would be inhibited or prevented. It would also be desirable if such a chemical would not only prevent such deposits but would also remove them without necessitating the stoppage of a given operation. It therefore becomes an object of the present invention to prevent the formation of high temperature deposits on metal surfaces by chemical means.

20 Another object is to furnish a chemical which when added to a hydrocarbon liquid will prevent the deposit-forming tendencies of said liquid when it contacts metal surfaces at elevated temperatures.

25 A further object is to provide a chemical treatment which will prevent the formation of high temperature deposits by petroleum hydrocarbon liquids in contact with heat transfer equipment.

30 Yet another object is to furnish a chemical treatment capable of being combined with a thermally unstable, deposit-forming liquid whereby said liquid will not form deposits upon metal surfaces at elevated temperatures.

35 Still another object is to provide a chemical treatment which will remove high temperature deposits from metal surfaces of petroleum refining equipment without the necessity of stopping the operations of such equipment. Other objects will appear hereinafter.

40 We have now discovered a process of preventing, inhibiting and/or reducing the formation of surface deposits from petroleum hydrocarbon liquids during the processing thereof at elevated temperatures such as from about 150–1000° F. (i.e. the adhesion of deposits to heat exchange metal surfaces) by adding to the hydrocarbon liquid such as by solution and/or dispersion an anti-fouling amount of an oxyalkylated N-substituted phenylene diamine, as exemplified by oxyalkylated N-phenyl-p-phenylene diamine, oxyalkylated N,N'-diphenyl-p-phenylene diamine and oxyalkylated N-cyclohexyl-N'-phenyl-p-phenylene diamine. Other additives can also be employed in conjunction with the above anti-foulants.

45 50 The anti-fouling additive system of this invention can be employed in refining crude petroleum as well as in the treatment of any component thereof which are exposed to high temperatures including the light distillates, for example light naphthas, intermediate naphthas, heavy naphthas, etc.; middle distillates, for example kerosene, gas, oil, etc.; distillate lube oil stocks for example, white oil, saturating oil, light lube oil, medium lube oil, heavy lube oil, and the like.

55 60 In addition, the additive can be employed with other hydrocarbons such as xylene, benzene, purified hydrocarbon compounds, etc. In addition, they can be employed under certain conditions with non-hydrocarbons, such as alcohols, phenols, etc. For example, they can be employed in a toluene extraction tower and stripper which process

65 70 comprises mixing phenol and toluene in an extraction whereby phenol extracts impurities from toluene and the raffinate is subsequently removed. Thereafter the mixture is sent to a stripper where the toluene is removed from the phenol by distillation. The remaining phenol is recycled to the extractor for further use. The system is operated over a wide temperature range, for example 230–425° F. Deposits in the phenol circuit cause the loss of

excessive amounts of phenol. It can be used in heat transfer units used in a furfural extraction process, processing for example, intermediate distillates, paraffin distillates, decanted oil, vacuum cylinder stock, deasphalted cylinder stock, etc.

The amount of anti-fouling agent required in this invention is subject to wide variation but in general very effective results have been obtained by adding relatively minute amounts of the anti-fouling agent to the hydrocarbon liquid being processed, for example, amounts may be as low as 0.5 p.p.m. in hydrocarbon liquid, for example 1 to 500 p.p.m. or higher, for example 1000 or more p.p.m., preferably 1 to 100 p.p.m., with an optimum of 3-30 p.p.m. In general, the upper limit is determined by the economics of the process but other factors should be taken into consideration, such as whether large amounts will have any adverse effects on present or subsequent operations. Because of the many different types of operations where hydrocarbons are heated to elevated temperatures under conditions where deposits are formed, it is difficult to give specific ranges which will be effective in all operations. The amount of agent which inhibits the formation of deposits is referred to herein as an "anti-fouling amount." The above figures relate to p.p.m. in terms of active anti-fouling chemical not including the solvent employed.

Inasmuch as the anti-fouling agent is employed in such small amounts and it is preferable to feed them continuously or semi-continuously by means of a proportioning pump or other suitable device to the particular hydrocarbon liquid being processed or to add them in a similar manner to the apparatus in which the hydrocarbon liquid is being processed, it is desirable to incorporate the agent or a mixture of agents into a suitable solvent which will be compatible with the liquid which is to be processed. The solvent which is used to dissolve the active ingredient is also subject to some variation depending upon the solubility characteristics of the particular compound employed. In some cases, even though the active mixture is insoluble in a particular solvent, it will dissolve in a combination of solvents.

In the practice of the invention it is very desirable to start the treatment with the chemicals employed for the purpose of the invention at a higher dosage and then gradually reduce the dosage to the point where fouling of the apparatus is just eliminated.

The invention is especially valuable where sour naphthas are being processed or where the oil being processed is a mixture containing some sour naphthas.

Examples of specific types of apparatus to which the chemical compositions of the invention can be added during petroleum processing are fractionating towers, stripping columns, debutanizers, depropanizers, deethanizers, heat exchangers, reboilers, hot product lines and other metal equipment (usually ferrous metal) which is brought into contact with the organic liquids being processed at relatively high temperatures. The invention makes it possible to extend the useful life of crude oil fractionating towers and other types of petroleum refinery equipment. It also makes it possible to provide cleaner inside surfaces resulting in better fractionation, better heat exchange in coolers, far less severe plugging and less time required for cleaning and maintenance.

The anti-fouling agents of this invention are oxyalkylated N-substituted phenylene-diamines as exemplified by oxyalkylated N-mono-substituted and N,N-disubstituted p-phenylenediamines, i.e., p-phenylene diamines containing alkyl-, isoalkyl-, cycloalkyl-, aryl- etc., radicals in varying combinations attached to the nitrogen atoms. These include oxyalkylated p-phenylene diamines such as oxyalkylated N,N'-diphenyl-p-phenylene diamine, N-cyclohexyl-N'-phenyl-p-phenylene diamine, and N,N'-di-sec-butyl-p-phenylene diamine.

Other derivatives include for instance oxyalkylated N-isopropyl-N'-phenyl-, N-isohexyl-N'-phenyl-, N-isooctyl-

N'-phenyl, N-phenyl-, N,N'-di-isopropyl, N,N'-diisobutyl, N,N'-di-octyl, and N,N'-dicyclohexyl p-phenylene diamine.

These oxyalkylated phenylene diamines are prepared according to the methods disclosed in S.N. 681,013, filed Nov. 6, 1967, now abandoned, which is by reference incorporated into this application as part hereof.

Oxyalkylated of the phenylene diamines is effected by employing suitable alkylene oxides or equivalent compounds.

The term "alkylene oxide," as used herein means a compound containing the following 1,2-epoxy group, also called an oxirane group, i.e.

and wherein each unsatisfied epoxy carbon valence of said group is satisfied for example by hydrogen, a hydrocarbon radical, a substituted group for example an ether-containing group, a halogen-containing group, or other radicals which do not interfere with the polymerization process. In addition, the unsatisfied epoxy carbon valences collectively can represent a divalent aliphatic hydrocarbon radical which together with the epoxy carbon atoms form a ring containing, for example, from 5 to 10 carbon atoms inclusive. It is to be understood, also, that the term "lower alkylene oxides" designates that each unsatisfied epoxy carbon valence of the above-depicted structural unit can be satisfied by hydrogen, a lower alkyl, e.g. methyl, ethyl, propyl, etc., substituted derivatives thereof, and the like.

For example, the monomeric alkylene oxides employed are vicinal-epoxyhydrocarbons which have a single vicinal epoxy group which can be characterized by the following formula:

wherein R₁, R₂ and R₃ are hydrogen, a hydrocarbon radical, a haloalkyl or aryl radical, an ether-containing radical or other types that do not interfere with the polymerization procedures such as certain nitrogen-containing derivatives sulfur-containing groups, ester groups, etc. Where R₁, R₂ and R₃ are hydrogen, the oxide is ethylene oxide.

Representative alkylene oxide monomers which can be employed are those in which R₂ and R₃ are hydrogen and R₁ is an organic radical such as alkyl, aryl, halogen-containing alkyl or aryl, ether-containing alkyl or aryl, unsaturated alkyl, ester-containing alkyl or aryl or mixtures of these types. Specific examples are ethylene oxide (where R₁ is also hydrogen), 1,2-pentene oxide, 1,2-hexene oxide, 1,2-octene oxide, 1,2-decene oxide, 1,2-dodecene oxide, propylene oxide, 1,2-butylene oxide, higher 1,2-epoxy alkanes, styrene oxide, o, m, or p-alkyl-styrene oxide, epihalohydrins such as epichlorohydrin, epibromohydrin, epifluorohydrin, 1,1,1-trifluoro-2-propylene oxide, chlorostyrene oxide, methyl glycidyl ether, ethyl glycidyl ether, isopropyl glycidyl ether, methyl glycidyl ether of propylene glycol, methyl glycidyl ether of dipropylene glycol, methyl glycidyl ether of tripropylene glycol, hexyl glycidyl ether, b-chloroethyl glycidyl ether, phenyl glycidyl ether, benzyl glycidyl ether o-, m-, and p-chlorophenyl glycidyl ether, o-, m-, and p-methylphenyl glycidyl ether, butadiene monoxide, chloroprene monoxide, allyl glycidyl ether, glycidyl methacrylate, glycidyl pivalate, trimethylsilyl glycidyl ether, butyl glycidyl formal, diethylglycidyl amine, N-(2,3-epoxypropyl) morpholine, N,N-dimethyl aminoethyl glycidyl ether, etc.

Other representative epoxides which can be used are those in which R₃ is hydrogen and both R₁ and R₂ are organic radicals generally defined as above for R₁. Specific examples are, isobutylene oxide, α -methyl styrene oxide, 1,1-diphenylethylene oxide, 1,1,1-trifluoro-2-methyl-2-propylene oxide, methyl methacrylate oxide, methylene cyclohexane oxide, etc.

Other representative epoxides which can be employed are those in which R_2 is hydrogen and R_1 and R_3 are organic radicals generally defined as above. Specific examples are cis- and trans- 2-butene oxide, 1,1,1-trifluoro-2-butene oxide, cyclohexene oxide, vinyl cyclohexene oxide, etc.

Trisubstituted ethylene oxides can also be employed in which R_1 , and R_2 and R_3 are all organic radicals as defined above. Trimethyl ethylene oxide is illustrative of this type. Furthermore tetrasubstituted ethylene oxides may be employed such as tetramethyl ethylene oxide.

The oxyalkylation may be carried out with one alkylene oxide, such as for example ethylene oxide, etc., so as to yield a homo-oxyalkylate; a mixture of alkylene oxides, such as for example a mixture of ethylene and propylene oxides, so as to yield a hetero-oxyalkylate; al-

marized in Table I. Example 6 is carried out without catalyst or solvent wherein epichlorohydrin acts both as reactant and solvent.

EXAMPLE 4

5 A solution of 0.15 mole of N-cyclohexyl-N'-phenyl-p-phenylene-diamine (39.9 gm.) and 119.7 gm. dimethyl formamide with 2 M percent $BF_3 \cdot OEt_2$ catalyst is placed in the pressure reactor. A 0.30 mole quantity 13.4 g. of ethylene oxide is added. The reactants are heated to 140° 10 C. for 8 hours. A pressure drop in the reaction indicates consumption of ethylene oxide. The product is removed from the reactor and dimethyl formamide is stripped off under vacuum. An infrared analysis of the product indicates that ethylene oxide has replaced the hydrogens on 15 both nitrogens.

TABLE I.—OXYALKYLATED N-SUBSTITUTED p-PHENYLENEDIAMINES¹

Ex.	R	R ¹	Mole of diamine	Name	Mole percent based on diamine	Solvent	Alkylene oxides			Comments
							Name	Mole	Comments	
1	phenyl	H	0.10	$BF_3 \cdot OEt_2$	2	Dimethyl formamide.	ECH ²	0.1

3	phenyl	H	0.15	$BF_3 \cdot OEt_2$	2	do	EtO^3	0.65	4.1 moles EtO per mole of diamine consumed.	
4	phenyl	cyclohexyl	0.15	$BF_3 \cdot OEt_2$	2	do	EtO^3	0.30	2 moles EtO per mole of diamine consumed.	
5	phenyl	cyclohexyl	0.10	$BF_3 \cdot OEt_2$	2	do	ECH ²	0.10		
6	phenyl	cyclohexyl	1.0		2	do	ECH ²	4.0	Reflux 5 hrs., remove excess ECH, 2 moles consumed.	
7	phenyl	cyclohexyl	1	$BF_3 \cdot OEt_2^4$	-----	Dimethyl formamide.	EtO^3	5.95	Moles consumed.	
8	phenyl	cyclohexyl	1	$BF_3 \cdot OEt_2^4$	-----	do	EtO^3	14.01	Do.	
9	phenyl	cyclohexyl	1	$BF_3 \cdot OEt_2^4$	-----	do	PrO^5	1.99	Do.	
10	phenyl	cyclohexyl	1	$BF_3 \cdot OEt_2^4$	-----	do	PrO^5	11.85	Do.	
11	phenyl	H	1	$BF_3 \cdot OEt_2^4$	-----	do	EtO^3	5.00	Do.	

¹ Unsubstituted phenylene diamine, i.e. NH_2 can also be similarly oxyalkylated to yield oxyalkylated phenylene diamines.

² ECH = Epichlorohydrin.

³ EtO = Ethylene oxide.

⁴ Sufficient $BF_3 \cdot OEt_2$ was employed to initiate the oxyalkylation and NaOH was then added to complete it.

⁵ PrO = Propylene oxide.

ternate additions of different oxides, such as first ethylene then propylene oxide, so as to yield a block oxyalkylate. In addition, one or more of the block oxyalkylate units may be hetero, etc.

The phenylenediamine may be oxyalkylated at least one or more of the nitrogen-bonded hydrogens, up to all available N-bonded hydrogens. In certain instances it may be difficult to oxyalkylate all N-bonded hydrogens. The phenylenediamine may contain 1 or more moles of oxyalkylate per molecule, such as one mole for each available nitrogen hydrogen.

In addition, the oxyalkylate may contain more than one mole of oxyalkylate per molecule such as for example 1-5, 1-10 moles or more. Where desirable more than 10 moles or more can be employed, such as 50-100 or more moles.

Thus, the phenylenediamine may be represented by

where R is a nitrogen-bonded radical, preferably a hydrocarbon, OA is a moiety of the alkylene oxide, n is the number of oxyalkyl groups, and m is a number determined by the number of active N-hydrogens on the phenylenediamine, such as for Examples 1-3.

Those nitrogen-bonded groups on the phenylenediamine groups which are not substituted with R or $(OA)_nH$ are hydrogen.

The following examples are presented for purposes of illustration and not of limitation. Since all of the examples described in the table were prepared in the manner of Example 4, to save repetitive details, they are sum-

45 The phenylenediamines are also oxyalkylated under similar conditions with butylene oxide. They are also oxyalkylated with mixtures of alkylene oxides to yield a heterooxyalkylate such as mixed ethylene-propylene oxides; alternately with one alkylene oxide and then with another oxide to yield block oxyalkylates such as a block 50 of ethylene oxide, then a second block of another oxide such as propylene oxide, etc.

The oxyalkylate is also carried out by taking the oxyalkylate produced with the Lewis acid, as in the above table, and continuing oxyalkylation with an anionic catalyst such as with a basic catalyst (e.g. NaOH, KOH, etc.). This was done in Examples 7-11.

In addition to the anti-foulant, other auxiliary additives may also be employed to enhance the anti-foulant function of the anti-foulant.

60 One auxiliary additive is a copolymer derived from an acrylic ester of the formula

65 and N-vinyl-2-pyrrolidone, for example a copolymer containing the following units:

70 75 having a molecular weight for example of at least 50,000,

for example 50,000-500,000, or higher, but preferably 100,000-400,000 with an optimum of 300,000-400,000 of which vinyl pyrrolidone comprises at least 1% by weight of the copolymer, for example 1-30%, but preferably 3-15% with an optimum of 5-10%; where Y is hydrogen, a lower alkyl group such as methyl, ethyl, etc., Z is an hydrocarbon group having, for example, 1-30 carbon atoms, but preferably 8-18 carbon atoms. These polymers are preferably acrylic or methacrylic polymers or polymers derived from both in conjunction with vinyl pyrrolidone. The Z group on the polymer, which can be the same throughout or mixed, can be octyl, nonyl, decyl, undecyl, dodecyl, tridecyl, tetradecyl, pentadecyl, octadecyl, etc. Lower alkyl groups can also be employed such as methyl, ethyl, propyl, butyl, pentyl, hexyl, heptyl, etc., but they preferably are employed as copolymers of the higher Z groups, for example a copolymer of dodecyl methacrylate and methyl acrylate, etc. The acrylic ester units may be derived from one or more acrylic type monomers and may be fully acrylic or fully methacrylic or both acrylic and methacrylic. The polymer may be random, block graft, etc.

Also, Z may also be an alkylated aromatic group such as butyl phenyl, amyl phenyl, etc., or a cycloaliphatic group such as cyclohexyl. Thus, non-limiting specific examples of suitable monomeric esters are: methyl acrylate, ethyl acrylate, propyl methacrylate, amyl acrylate, lauryl acrylate, lauryl methacrylate, cetyl methacrylate, octadecyl methacrylate, amylphenyl methacrylate, cyclohexyl methacrylate, etc., including the analogous acylate of methacrylate esters. Copolymers of the above and other acrylic esters may be used, for example, a copolymer of methyl or ethyl acrylate and dodecyl methacrylate in conjunction with vinyl pyrrolidone. However, it should be understood that this description does not preclude the presence of small amounts of unesterified groups being present in the polymer, i.e., approximately 5% or less of where Z=H.

It should be understood, of course, that when the above compounds are polymerized, the polymerization should not be carried to such an extent as to form polymers which are insoluble or non-dispersible in the petroleum hydrocarbon used. The polymerization may be carried out by methods known to the art, such as by heating mildly in the presence of a small amount of benzoyl peroxide, but the method of polymerization is not part of this invention. For examples of acrylic-vinyl pyrrolidone copolymers see French Pat. 1,163,033.

The following are some illustrative examples of vinyl pyrrolidone-acrylic ester type resins which can be employed in this invention.

TABLE A.—VINYL PYRROLIDONE-ACRYLIC ESTER-TYPE RESINS

Monomer 1	Monomer 2	Monomer 3	Vinyl pyrrolidone, percent by weight	Mol ratio 1:2:3	Avg. mol. weight
Example:					
1(a)-----Tridecyl methacrylate.	Octadecyl methacrylate.	-----	7.5	1:1	300,000
2(a)-----Dodecyl methacrylate.	-----	-----	10	-----	500,000
3(a)-----do	Butyl acrylate.	-----	15	2:1	400,000
4(a)-----Octadecyl methacrylate.	-----	-----	5	-----	450,000
5(a)-----Tridecyl methacrylate.	-----	-----	20	-----	350,000
6(a)-----Octadecyl methacrylate.	ethyl methacrylate.	-----	10	3:1	500,000
7(a)-----Dodecyl methacrylate.	Ethyl acrylate.	-----	5	4:1	400,000
8(a)-----Cetyl methacrylate.	Octadecyl methacrylate.	Butyl methacrylate.	7.5	2:1:0.5	350,000

EXAMPLE 9(a)

Another illustrative example of a vinyl pyrrolidone-acrylic ester type resin, hereinafter referred to as Additive VPA, which can be employed in this invention, is prepared by polymerizing 65 parts by weight of an alkyl methacrylate, where the alkyl portion is obtained from a commercial cut of C₁₂ to C₁₈ fatty alcohols, 25 parts by weight of butyl methacrylate, and 10 parts by weight

of N-vinyl pyrrolidone. In making this ester type resin by polymerization 0.075 part, by weight of the monomer mixture, of benzoyl peroxide is added to said mixture, and the so-formed mixture is stirred and warmed to dissolve the benzoyl peroxide. Then, 20 parts, by weight of said mixture, of a white mineral oil is added to a reaction vessel which is swept out with nitrogen gas, and the so-formed mixture is slowly added to said white mineral oil in said reaction vessel over a two hour period. At 2.6 hours, 0.015 part, by weight of said monomer mixture, of benzoyl peroxide is added to the vessel. Then, at 4, 4.6, 5.3 and 6 hours, respectively, further additions of 0.022 part, by weight of said monomer mixture, are made and during this time and until 9-10 hours, when heating is discontinued, temperatures are maintained between 97° C. and 103° C. At 6.5 hours, 28 parts of white mineral oil are added, and the batch is stripped of volatile products by being heated up to 145° C. at 2 mm. pressure, giving a yield of about 90% of copolymer having an average molecular weight of 450,000.

Another auxiliary additives is a metal deactivator, for example, those conveniently employed in deactivating copper, iron and other metals from hydrocarbon systems. Typical examples are those described in U.S. Pat. 2,282,513. Of course, one skilled in the art is aware that many other metal deactivators are known and can be employed herein.

The compounds employed as metal deactivators are preferably of the type of Schiff's bases and may be represented by the formulae

and preferably,

wherein A and B each represents an organic radical and preferably a hydrocarbon radical. In Formula (1)A and B each preferably represents a hydrocarbon radical. In Formula (2)A and B each preferably represents an aromatic ring or an unsaturated heterocyclic ring in which the hydroxyl radical is attached directly to a ring carbon atom ortho to the —CH=N group, R represents an aliphatic radical having the two N atoms attached directly to different carbon atoms of the same open chain. The preferred metal deactivator is that former from salicylaldehyde and 1,3-propylenediamine.

Typical examples of aldehyde and polyamines employed in preparing these Schiff bases include the following:

Aldehydes

Benzaldehyde

2-methylbenzaldehyde

 1,2-diamino-cyclohexane
 Di-(*b*-aminoethyl) ether
 Di-(*b*-aminoethyl) sulfide

Where auxiliary additives are employed, the ratio of these additives to the anti-foulant can also vary widely. In general the weight ratio of anti-foulant to the acrylic-type polymer is at least 1:1, from about 1:1 to 100:1 such

as about 2:1 to 50:1, for example, from about 3:1 to 20:1 but preferably from about 5:1 to 15:1.

In general, the ratio of anti-foulant to metal deactivators is at least about 1:1, from about 1:1 to 100:1 such as about 2:1 to 50:1, for example from about 3:1 to 20:1 but preferably about 5:1 to 15:1.

The following examples are presented for purposes of illustration and not of limitation.

The tests were carried out according to the following procedure:

TEST PROCEDURES

The apparatus for the test measurements makes use of a heat exchanger and the loss of heat transfer is used as a criteria for evaluating the fouling rate. The method utilizes a controlled temperature test chamber containing a single $\frac{1}{8}$ " stainless steel tube heat exchanger. Crude oil is fed through this tube and the degree of fouling is measured and recorded continuously by a change in the temperature differential of the inlet and outlet temperature of the test section. By controlling the temperature, pressure and flow rates, the fouling characteristics of both crude oil and refinery charge stocks, with and without anti-foulant compounds can be readily determined under conditions approaching those of an operating refinery.

In these tests, the anti-foulant, when used, is blended with the desalted crude oil in a reservoir held at room temperature. This desalted crude is pumped by means of a high pressure pump into the furnace where the crude oil enters and passes through a heat exchanger. The temperature is measured at the entrance and exit points of the heat exchanger and the difference between these two temperatures (ΔT) is continuously recorded. In tests where little or no fouling occurs in the heat exchanger the change in this temperature difference remains fairly constant or zero with time. As fouling occurs this temperature differential will change with time, increasing in value as fouling occurs. A test run normally lasts 4-6 hours. A clean $\frac{1}{4}$ " O.D. preheat section and a new heat exchanger section are used for each run.

Test data are presented in the following tables.

TABLE II

Although the invention has been described with reference to preferred embodiments thereof, it is understood that the description is by way of illustration only. Accordingly it is contemplated that modifications and variations can be made by those skilled in the art in light of my description without departing from the spirit of the invention.

Having thus described our invention what we claim as new and desire to obtain by Letters Patent is:

1. A process of inhibiting in hydrocarbon refinery operations at elevated temperatures the adhesion of deposits on heat transfer surfaces of a heat exchanger which comprises incorporating into the hydrocarbon prior to contact with the heat exchanger an anti-foulant amount of an oxyalkylated N-substituted phenylene diamine.

2. The process of claim 1 where the phenylene diamine prior to oxyalkylation has the formula

where R is phenyl and R' is either H or cyclohexyl.

3. The process of claim 2 where R' is hydrogen.

4. The process of claim 3 where the oxyalkylated N-substituted phenylene diamine has the formula

5. The process of claim 4 where the oxyalkylated N-substituted phenylene diamine has the formula

6. The process of claim 1 where a vinyl pyrrolidone-acrylic type ester is also employed.

7. The process of claim 2 where a vinyl pyrrolidone-acrylic type ester is also employed.

8. The process of claim 3 where a vinyl pyrrolidone-acrylic type ester is also employed.

9. The process of claim 4 where a vinyl pyrrolidone-acrylic type ester is also employed.

10. The process of claim 5 where a vinyl pyrrolidone-acrylic type ester is also employed.
